UNITED STATES PATENT OFFICE.

GIDEON F. KIBLINGER, OF FISHERSVILLE, VIRGINIA.

ENSILAGE-PACKER FOR SILOS.

1,294,674.

Specification of Letters Patent. Patented Feb. 18, 1919.

Application filed October 12, 1917. Serial No. 196,272.

To all whom it may concern:

Be it known that I, GIDEON F. KIBLINGER, a citizen of the United States, residing at Fishersville, in the county of Augusta, State 5 of Virginia, have invented certain new and useful Improvements in Ensilage-Packers for Silos; and I do hereby declare the following to be a full, clear, and exact description of the invention, such as will enable 10 others skilled in the art to which it appertains to make and use the same.

This invention relates to improvements in packing devices and particularly to devices 15 for packing ensilage in a silo, as the ensilage is delivered thereinto.

One object of the present invention is to provide a novel and efficient device of this character by means of which the center and edges of the ensilage will be packed with 20 equal firmness and solidity.

Another object is to provide a novel device of this character which will automatically rise as the level of the ensilage in the silo rises, until the silo is filled to the top, or 25 the desired level.

Other objects and advantages will be apparent from the following description when taken in connection with the accompanying drawing.

80 In the drawings:

Figure 1 is a vertical longitudinal sectional view through a silo, showing my improved packing device in elevation therein.

Fig. 2 is a horizontal sectional view taken 85 on the line 2—2 of Fig. 1.

Fig. 3 is a horizontal sectional view taken on the line 3—3 of Fig. 1.

Fig. 4 is a vertical longitudinal sectional view through one of the tension arms 30.

40 Fig. 5 is an enlarged transverse sectional view taken on the line 5—5 of Fig. 3.

Fig. 6 is a sectional view similar to Fig. 1 showing the packing rollers elevated with the rise of ensilage in the silo.

45 Fig. 7 is a sectional detail of a modified form of mounting for the pressure roller.

Fig. 8 is a perspective view of the member 47", showing the lugs 47 which are received in the sockets 46 of the roller 41.

50 Fig. 9 is a perspective view of the roller 41, showing the sockets 46.

Referring particularly to the accompanying drawings, 10 represents a silo. Disposed vertically and centrally within the silo,

is a shaft 11 which is angular in cross section, the uppermost section 11' of which is slidably disposed through and is rotated by a pinion 12. The lower end of each of the sections of the shaft 11 is formed with a socket member 10' for the reception of the 55 upper end of the next lower section, a set screw 10" being carried by the socket member for securely clamping the sections together. A frame including radial arms 13 is disposed on the upper edge of the silo, and the ends of said arms are provided with downwardly turned fingers 14 for engagement with the upper edges of the walls of the silo, and clamping screws 15 for the purpose of holding the fingers to the wall are 60 carried by the fingers. In a bracket 16, carried by the said frame, there is supported a horizontal shaft 17, the inner end of which carries a pinion 17' meshing with the pinion 12, while the other end of the shaft carries 65 a loosely mounted sprocket wheel 18. This sprocket wheel is driven by means of the chain 19, from the ensilage cutting machine 20, shown in Fig. 1.

Extending upwardly from the cutting machine is a tubular blower pipe 21 having an elbow 22 at its upper end for discharging the ensilage into the upper end of the silo.

Carried by the lowermost section 11" of the shaft 11, is a transverse shaft 23, one 80 end of which extends to a point adjacent the inner face of the silo, while the other end is disposed a short distance at the other side of the lower end of the shaft 11. On the lower portion of the shaft 23 there is mounted a roller 24, and on the shaft, between the inner end of the roller and the bearing 25, which supports the shaft 23, is a coil spring 26, which normally urges the roller outwardly on the said shaft. This roller is arranged to pack the ensilage near the outer edge of the silo. On the other end of the shaft 23 is a roller 27, which turns in a circular path close to the lower end of the shaft 11, so as to pack the ensilage near or at the 85 center of the silo.

A suitable clutch 28 is carried by the horizontal shaft 17 for releasable engagement with the sprocket wheel 18 for starting or stopping the mechanism.

Carried by the section 11", at a suitable 90 distance above the rollers 27 is a rigidly secured collar 29, and slidably engaged on the

said section, above this collar, is a transversely disposed bar 30. Disposed vertically through the end portions of this bar are the bolts 31 which are received in the longitudinal slots 32 formed in the adjustable arms 33 which arms are disposed on the said end portions. The ends of the arms are bifurcated, as at 34, and pivotally mounted in each of the said bifurcations 5 is a friction member 35 which is adapted to bear against the inner face of the silo wall. Connected to each of the pivoted friction members is a cord or wire 36 which extends inwardly toward the center of the 10 silo and downwardly through the central opening in the bar 30, as shown at 30', where the depending end carries a weight 37. These weights serve to hold the friction members firmly against the silo wall so that 15 the upward pressure of the packing silage against the rollers will be resisted to such a degree that the silage will be properly and firmly packed. When the pressure gets to a point beyond the frictional holding 20 power of the said members the bar and arms will be automatically pushed upwardly and in this event the uppermost section which slides through the pinion 12, is removed and the next lower section placed through 25 the said pinion. This is repeated until the mounting level of the ensilage has reached 30 a point adjacent the top of the silo.

The clutch 28 is automatic in its action, and is held in engagement with the member 35 28' of the shaft by means of the spring 38, whereby should the driving mechanism tend to bind the clutch will turn idly without 35 acting on the shaft 17, thereby preventing the breaking of any of the parts of the 40 mechanism.

It will be noted that the outer end of the roller 24 is rounded, as shown at 24', whereby any binding between the roller and the side wall of the silo is prevented.

45 Referring particularly to Fig. 7 there is shown a modified form of roller. In this form the shaft 39 has telescopically slideable thereon the hollow shaft section 40 on which is secured the roller 41. The inner 50 end of the hollow shaft 40 is formed with an enlarged portion 42 which carries a set screw 42' whereby the said shaft is capable of being secured in different longitudinal positions on the shaft 39, and thereby place 55 the roller 41 closer to or farther from the side wall of the silo. This is especially useful in connection with silos of different diameters, and where the form shown in the other figures will not be long enough. The 60 outer end of the hollow shaft is formed with a flange 45 which prevents the removal of the roller from the shaft, while at the same time permits the roller a free rotary movement on the shaft.

The outer or larger end of the roller 41 65 is formed with a peripheral series of sockets 46 which receive the lugs 47 carried by an end section 47' which is secured detachably to the end of the roller by means of the screws 48. Thus the roller is capable of 70 being lengthened should the adjustment of the shafts 39 and 40 be insufficient.

What is claimed is:

1. An ensilage packing device for a silo including a vertical rotatable sectional shaft 75 suitably supported within the silo, means for driving the shaft, a transverse shaft mounted on the lower end of the vertical shaft, one end of said transverse shaft extending to a point adjacent the side of the 80 silo while the other end is disposed a short distance beyond the other side of the vertical shaft, a roller mounted on the shorter portion of the transverse shaft, and a spring pressed roller mounted on the longer portion 85 of the transverse shaft.

2. An ensilage packing device for a silo including a centrally located vertical sectional shaft, means for rotating the shaft, the shaft being detachably connected to the 90 rotating means, packing elements carried by the shaft, and an automatic tension means for the packing elements and shaft.

3. An ensilage packing device for a silo including a vertical rotatable shaft, packing 95 elements carried by the lower end of the shaft, a stop collar on the shaft, adjacent the lower end thereof, a transverse bar slidably disposed on the shaft above the collar, and gravity actuated gripping means 100 on the ends of the bar for engagement with the walls of the silo to hold the packing elements in firm engagement with the ensilage.

4. An ensilage packing device for a silo 105 including a vertical rotatable shaft, packing rollers mounted on the lower end of the shaft and movable with the shaft, a stop collar on the shaft above the rollers, a transverse bar on the shaft above and engaging with the 110 collar, friction elements carried by the ends of the bar for engagement with the walls of the silo to exert downward pressure on the packing elements, the center of the bar being provided with an opening for the reception of the shaft, flexible elements connected to the friction elements and extending 115 downwardly through the said opening, and weights carried by the depending ends of the flexible elements.

5. In a silo packing device a vertical rotatable shaft, horizontally disposed packing rollers mounted on the lower end of the shaft, one of said rollers being longitudinally adjustable toward and away from 125 the wall of the silo and removably connected to the shaft.

6. A silo packing device including a ver-

tical rotatable shaft, horizontal shafts carried by the lower end of the vertical shaft, a roller carried by one of the said shafts, a hollow shaft longitudinally adjustable on the other shaft, a roller rotatably mounted on the hollow shaft, and a detachable roller end section carried by said adjustable roller.

In testimony whereof I affix my signature in the presence of two witnesses.

GIDEON F. KIBLINGER.
